(57) **CLAIM**

The ornamental design for a finger support for weapons, as shown and described.

DESCRIPTION

1.Straight finger support for weapons.

2.Curved Finger support for weapons.

1.1 : Front;

1.2 : Back;

1.3 : Perspective;

1.4 : Perspective;

1.5 : Perspective;

2.1 : Front;

2.2 : Back;

2.3 : Perspective;

2.4 : Perspective; and

2.5 : Perspective.

The reproductions 1.5 and 2.5 are referential perspective views showing the state in use of the claimed designs and form no part thereof; reproductions 1.3-1.4 and 2.3-2.4 show the claimed designs in a disassembled state, whereas reproductions 1.1-1.2 and 2.1-2.2 in an assembled state.
